UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

WEB-PRINTING MACHINE.

1,307,390.

Specification of Letters Patent. Patented June 24, 1919.

Application filed April 2, 1918. Serial No. 226,235.

To all whom it may concern:

Be it known that I, HENRY A. WISE WOOD, a citizen of the United States, residing at New York, in the county of New York and 5 State of New York, have invented a new and useful Web-Printing Machine, of which the following is a specification.

This invention relates to the art of web printing, and the principal objects thereof 10 are to provide for very materially increasing the speed of a rotary web printing press, particularly of the newspaper type, without increasing the normal tractive running strain upon the web; without increasing the 15 tendency to tear the web upon the indentation of the paper by means of the type; without necessitating the use of any better paper than that commonly employed at the present time; and more specifically, to accomplish 20 these results simply by providing a surplus of paper in a relatively loosened condition at the point and moment of impression in order to release the web from excessive strain and compensate for the 25 stretching effect due to the impression of the type thereon.

By accomplishing these results, newspaper offices can materially increase their output with substantially one half the number of 30 machines now used, occupying half of the space and employing half the number of press men, or still better they can print their edition in substantially one half the time. This is the most valuable of all considerations 35 in the production of newspapers. Further objects and advantages of the invention will appear hereinafter.

Reference is to be had to the accompanying drawing which is a longitudinal sectional view of a common form of rotary web printing press illustrating the application of this invention thereto.

A rotary newspaper printing machine takes paper from a roll, prints it upon one 45 side, and then on the other, folds, cuts, and delivers it in the form of a newspaper. The speed of this machine and its successful operation depend upon its freedom from paper breakage more than upon any other single 50 factor. Presses in present day use have an ordinary running speed ranging from twenty-two thousand copies per hour per folding machine to thirty-six thousand copies. Beyond the latter speed, paper 55 breakage and the consequent wastage of

paper and time become too great for practicability.

The impression of the sheet between the plate carrying cylinder and the impression cylinder, which is covered with soft packing, 60 is really an embossing operation, that is, the type has an embossing effect upon the sheet. This is due to the fact that the type surfaces project beyond the normal surface of the sheet and act like teeth. This necessarily 65 gathers more paper into the printing cylinders during the passage of each plate than would occur if it passed over the plates without impression. This embossing effect is 70 seemingly minute, but it is sufficient to produce a condition of such tension that the occurrence of an additional unaccommodated strain upon the paper will almost invariably cause a breakage. It is this gathering up of the paper under strain upon the tooth-like 75 type that creates the condition of danger for the paper, which requires only a weak spot, a crack in the web, a type cut, or a slight overstrain upon it, to snap the web and throw the press into confusion. 80

Thus stoppages of the press for the purpose of clearing it of torn paper and threading it with a fresh length of paper frequently happen. They take up time, frequently as much as a quarter of an hour, 85 that is seriously felt in the production of a newspaper, because, as is well understood, delayed news is no news, and papers that are late are unsalable. The newspaper is the most perishable of all industrial products; also, delays frequently cause the loss of trains and so deprive out of town readers of their newspaper. 90

Now I find that a speed higher than those above mentioned places upon the paper of 95 the existing type of press an immense overstrain and that this is what causes fracture when these higher speeds are attempted, and has led to the failure of many attempts which have been made to increase the usual 100 speed.

Of course, the faster the web must be pulled forward the greater its tension, due to increased resistance, and furthermore the more rapidly the printing cylinders rotate 105 the quicker is the blow delivered by the sharp cornered type surfaces on the taut web. As newsprint paper is the cheapest of all papers and is intended to last only a few hours after being printed, it has been kept 110

down in quality and consequently in tensile strength to the lowest merchantable point. This point has been determined by the severity of the press conditions of the general user. As the general user runs his machines at the lower of the speeds heretofore named, the common run of paper furnished is that which will just about meet the requirements at that speed.

10 To meet all these limiting conditions, comprising the indentation or weakening of the paper by the tooth-like type surface, the normal tractive running strain upon the web, and the added tractive strain due to higher 15 speeds, without necessitating an increase in the quality and therefore in the cost of the paper, is the object of this invention.

To accomplish this object I feed the paper to the press with what I term a "flood feed," that is, I increase the speed of the paper as it 20 approaches the printing couples to a slightly higher velocity than that of the surfaces of the printing couples. This results in bringing the paper at the time of the impression 25 into a loose condition so that although the type embosses it as above explained and its sharp corners abut against it and press it out of its plane with a higher velocity than has been accomplished heretofore, they do 30 not have this effect at an instant when the paper is held taut or is running in a taut condition, but when it is slightly loose or free. Therefore the paper, when it is necessarily 35 stretched to increase its surface slightly on account of the embossing operation, has at hand the surplus stock necessary to compensate for this action, and the strain otherwise present does not exist. I find that by this 40 invention I have been able to raise the normal running speed to over two hundred and fifty per cent. of what it has been heretofore, and the maximum practicable speed to nearly two hundred per cent. thereof. In other words, instead of being limited to 45 from twenty-two thousand to thirty-six thousand copies per hour per folder I obtain from sixty to seventy thousand copies per hour per folder. The extraordinary importance of this may be seen from the fact that it has required several centuries of 50 development to achieve the speed of twenty-two to thirty-six thousand copies of newspapers per hour, and that this has been achieved only by numerous very gradual 55 steps in development, whereas, by this simple invention, the speed has been raised enormously in the revolutionary degree above indicated.

Referring now to the drawing, it shows 60 an ordinary type of newspaper machine having plate cylinders A, and impression cylinders B constituting the printing couples, and a feeding roller or paper supplying device C which supplies the printing couple with 65 paper from a paper roll D. This paper sup-

plying device is shown as provided with tapes K running-around tape pulleys or rollers for the purpose of securing a more positive feed. This is but one of many well-known paper supplying devices, any one of which may be adapted to the requirements of this invention. The web goes from the printing couples to an ordinary drag or draft roll E which draws the paper out of the press to a folding machine F of any usual construction. 70 Inking devices G of an ordinary pattern are shown. I have also illustrated a driving means in the form of a shaft H and bevel gears J for driving the rolls or drums C and E positively from the press. These drums 80 C and E are driven at a slightly higher surface speed than that of the printing couples A and B. This may be done by an increase through the gearing or by making them of a slightly greater diameter than would be 85 necessary to produce the exact speed of the printing couples. The printing couples, of course, may be organized and driven in accordance with any of the usual printing machines on the market.

It has been thought necessary heretofore to feed the paper at what is known as "press speed" to the printing couples, that is, having its speed, between the web roll D or a feeding device as C and the printing couples, 95 the speed of the latter. The main feature of this invention is that the incoming paper shall be fed to the printing couple faster than the surface speed of the printing couple. The drag roller E is run, as is always the case, with a surface speed slightly 100 faster than the printing couples, in order to keep the web taut between printing couples and folding machine. Therefore it has sufficient drawing-out capacity to take up such 105 surplus of web as the flood feeding system throws into the machine. Whatever excess of paper accumulates in the printing cylinders during the passage of a printing plate will be drawn out of the cylinders by the 110 drag roller during the passage of the succeeding margin. Therefore, the printing cylinders never can accumulate, because of my flood feeding, more paper than is drawn away from them by the drag roller during 115 each revolution of the printing couple. Thus, often the looseness of the flood feed has served its purpose; it is gathered up by the drag roll E and ceases to exist.

Heretofore it has been customary to run a 120 web taut throughout the whole length of the press, that is, from the paper supply to the folder, and, therefore, at the same speed throughout this entire mechanism. But I insure that the paper speed shall be faster 125 before the web enters the printing couples than their surface speed. It is run taut from the second printing couple to the folder as usual, but it run just sufficiently loose between the web supply and the last 130

printing couple to be free of tautness and strain and to supply any surplus paper needed for accomplishing the embossing operation. This has enabled me to more than 5 double the speed of a commercial newspaper press, and revolutionize the industry of newspaper printing.

- Because of the flood of paper that comes to the first printing couple, more paper 10 passes through the first printing couple than is actually needed by it, and this paper it is that floods the second printing couple; that is to say, the first printing couple gathers the paper up, as it were, by minute increments 15 between the lines of type, and passes the sum of these increments on to the second couple. The flood as applied to the first printing couple is made sufficient to cause this to occur.
- 20 Although I have shown and described the invention as applied to a single type of rotary newspaper press, I am aware of the fact that it may be applied to other types of rotary web printing machines and be carried out in other forms without departing 25 from the scope of the invention as expressed

in the claims. Therefore I do not wish to be limited in these respects but what I claim is—

1. In a web printing machine, the combination with the rotary printing couples, of means for feeding a web to the printing couples sufficiently in excess of their surface speed to leave the web between said feeding means and the printing couples free from 30 printing strain during the printing period.

2. In a web printing machine, the combination with one or more rotary printing couples, of means for feeding a web to the printing couples at a feeding velocity 40 slightly in excess of the printing velocity of the printing couples, so that a slight excess of paper shall be fed to the said couples.

3. A web printing machine comprising one or more rotary printing couples, and 45 means for feeding a web to the printing couples comprising a feeding device having a feeding speed slightly in excess of that of the printing couples.

In testimony whereof I have hereunto 50 affixed my signature.

HENRY A. WISE WOOD.
